STEREOSCOPIC APPARATUS

Charles D. Moriarty, Schenectady, N. Y., assignor
to General Electric Company, a corporation of
New York

Application December 7, 1937, Serial No. 178,534

8 Claims. (Cl. 33—1)

The present invention relates to improvements in stereoscopic apparatus.

It is one object of the invention to provide improved means whereby photographs or other observations which are limited to two dimensions may be used to provide accurate measurements in a third dimension.

More specifically, it is my object to provide a stereoscopic apparatus of such character that two dimensional observations of an object under consideration may be translated by mechanical means into measurements of such object in its third dimension. While not limited thereto, the invention is primarily applicable in connection with radiographic (X-ray) studies of human bodies, metal castings or other opaque objects in which it is desired to observe and locate accurately foreign elements or defects.

The features of novelty which I desire to protect herein will be pointed out with particularity in the appended claims. The invention itself together with further objects and advantages thereof may best be understood by reference to the following description taken in connection with the drawings in which Fig. 1 shows in perspective the complete apparatus; Fig. 2 is an incomplete or partial section taken centrally through the apparatus; Fig. 3 is a plan view of the operative elements of the apparatus; Fig. 4 is an enlarged detailed view of a fragmentary portion of Fig. 3; Fig. 5 is a fragmentary sectional view on line 5—5 of Fig. 4; Figs. 6 to 10 are diagrammatic representations useful in explaining the invention; Figs. 11 and 12 taken jointly, comprise a representation of a measuring device which comprises an important feature of the invention; Fig. 13 is a view on line 13—13 of Fig. 11; Fig. 14 is a view on line 14—14 of Fig. 11; Fig. 15 is a view on line 15—15 of Fig. 12 and Fig. 16 is a more or less diagrammatic view illustrating one mode of use of the measuring device of Fig. 11.

Referring to Fig. 1 it will be seen that the apparatus includes an elongated table 10, supported at its opposite ends by cooperating uprights 12 and 13. Means, (not shown) may be provided for raising and lowering the table to render its upper surface conveniently accessible to the operator.

Above the table and supported independently of it by the uprights 12 and 13 there are provided a pair of guide rails 15 and 16 which are shown as being joined at their ends by means of tie bars 17 and 18. A composite frame comprising a stationary outer part 20 and a relatively movable

inner part 21 (shown more clearly in Fig. 3) is suspended from the guide rails 15 and 16 by means of supporting brackets 23. A mirror 24, arranged normally to the plane of the table, rests on the upper surface of the frame 20 and is supported laterally by means of blocks 26 which are slidably mounted on the guide rails 15 and 16. The mirror is shown as being clamped to the frame 20, by means of thumb screws 27 and 28, but it is contemplated that these may be loosened when occasion requires to permit removal of the mirror.

The function of the table 10 and its relation to the other parts of the apparatus may best be understood by reference to Fig. 2 which shows a section taken through the table in the region of the mirror 24. From this view it will be seen that the table comprises a hollow structure which is closed at the top by means of a hinged cover including a plate of translucent material 28' such as glass. Within the confines of the table there are provided one or more light sources illustrated as electric lamps 30. These serve to throw light upwardly through the plate 28' and to illuminate photographs or other pictorial representations supported on the surface of the table. (In one contemplated use of the apparatus, such representations may comprise stereoscopically related X-ray photographs of a subject desired to be studied radiographically.) Another transparent plate 29, covering only a portion of the table area, may be laid on the surface of the plate 28' for anchoring and flattening the pictures to be viewed.

It is one function of the apparatus so far described to enable an object under consideration to be viewed stereoscopically. To this end, stereoscopically related views of the object may be supported on the upper surface of the table 10 on opposite sides of the mirror 24 as indicated at 31 and 32 in Fig. 3. As appears from this figure, these views are arranged symmetrically on opposite sides of the mirror but are so positioned as to face in opposite directions; that is, that portion of the image which is on the left in one view is on the right in the other view. Shades or screens 33 and 34 which are provided in connection with the upper surface of the table may be drawn to such a position as to frame the pictures under consideration and to concentrate the light transmitted from the lamps 30 (Fig. 2). The position of these shades may be controlled by means of handles 35 and 36 which are slidable on a guide rail 37.

Referring again to Fig. 1, if the eyes of an

observer are positioned with respect to the mirror 24 as indicated at 39 (or alternatively adjacent to the opposite side of the mirror), a stereoscopic image of the object under consideration 5 may be obtained. This may best be understood by reference to the diagrammatic representation of Fig. 6 in which the relation of the mirror 24 to the two stereoscopically related views 31 and 32 is shown as seen from the side. 10 The eyes of an observer are indicated at 43 and 44 respectively. It is assumed that the views 31 and 32 each include the picture or outline of an object desired to be viewed stereoscopically, say, the picture of a small round object such as a 15 spherical shot. These pictures are indicated in the relation which they are assumed to occupy in the views as a whole at D' and D'' respectively.

If the line of vision of the observer is directed 20 toward the right it will be seen that the picture D' will be viewed directly by the right eye 44, as indicated by the solid line rays d'. The picture D'' on the other hand will be viewed by the left eye as a reflection in the mirror 24, the manner 25 in which this picture is received by the eye being indicated by the solid line rays d''. Due to an optical illusion, however, the observer will have the impression of seeing, not the picture D'', but instead a virtual picture D''' adjacent to but displaced 30 from the picture D'. (The displacement is a result of the stereoscopic relation between the two views 31 and 32.)

The effect produced on the observer by this 35 simultaneous observation of two displaced images is to create the illusion of a composite image existing at D, the region of intersection of the rays d' and d''. By a phenomenon which is familiar to most persons, this stereoscopic image appears to be solid and to have extension in a third dimension. It can be readily shown that the apparent position in space of the stereoscopic image D is a function of the displacement between the pictures D' and D''' and consequently of the respective spacings of the pictures D' and D''' with 45 respect to the mirror 24. This is a fact which is utilized in the further aspects of the invention.

In addition to providing a stereoscopic image of an object under consideration, it is a further important function of my invention to provide 50 means for producing an indexing image which is capable of apparent motion in three dimensions so that it may act as a "pointer" with respect to any particular part of the object which is desired to be especially examined. Referring again to 55 Fig. 3, one form of indexing means is shown as comprising a pair of similar indexing elements 50 and 51 (preferably although not necessarily hairlines) positioned on opposite sides of the mirror 24 and each associated with one of the pictorial 60 representations 31 and 32. These indexing elements or hairlines are so mounted as to be movable convergently toward or divergently away from the mirror 24 or to be movable simultaneously in a common direction with respect to the 65 mirror. They may be viewed stereoscopically by means of the mirror 24 to provide a common indexing image having a desired optical relation to the object image.

Referring again to Fig. 6 it will be seen that 70 from the standpoint of an observer the hairline 51 is viewed directly along the ray b', and the hairline 50 is viewed indirectly by reflection as indicated by the ray b''. A virtual image of the latter hairline will also be seen in coincidence 75 with the hairline 51 as indicated by the ray b''.

and the effect of a stereoscopic image will be obtained. With the particular hairline positions selected, this stereoscopic image will appear to coincide with the surface of the photograph 32, due to the intersection of the rays b' and b'' at 5 such surface.

The effect of simultaneously moving the hairlines 50 and 51 convergently toward the mirror 24 is shown in Fig. 7 in which both hairlines are nearer to the mirror than in Fig. 6. From a comparison of these figures it appears that as long as this motion is symmetrical, that is, as long as each hairline is moved neither more nor less than the other hairline, the hairline image will remain in the same horizontal plane. It will however, 15 move in a direction transverse to the line of vision; that is to say, parallel to the surface on which the views 31 and 32 are supported. In the position shown in Fig. 7 the hairline image would appear to the observer to be directly behind the 20 object image D.

The effect of moving the hairlines 50 and 51 simultaneously in the same direction (i. e. to the right or left) is shown in Fig. 8 in which the hairlines are represented as having each been 25 shifted slightly to the left from the positions which they occupy in Fig. 7. The effect of the particular extent of motion indicated is such as to bring the hairlines into substantial coincidence with the stereoscopically related views D' and D'' 30 of the object D. Consequently the composite image of the hairlines must necessarily appear to coincide spatially with the object image D. In other words, the hairline image has apparently been caused to move in a third dimension, that is, 35 in a direction parallel to the line of vision.

If the hairlines are now again moved symmetrically so as to converge toward the mirror 24 in the manner described in connection with Fig. 7, further motion of their image in a plane transverse 40 to the line of vision will occur. As appears in Fig. 9, such symmetrical hairline motion will not produce displacement of the hairline image parallel to the line of vision, but will cause it to scan a plane 38 parallel to the surface of support of the 45 views 31 and 32.

The practical importance of the facts just described consists in the fact that the observer or operator can voluntarily control the position of the hairline image to cause it to coincide precisely 50 with the apparent position of the object image, no matter where such image may be. By means which will be hereinafter described the steps taken in producing such coincidence can also be made to furnish desired measurements with respect to the object under consideration. 55

For causing apparent motion of the hairline image in a direction transverse to the observer's line of vision there is provided means for effecting simultaneous and symmetrical motion of the 60 hairlines with respect to the mirror 24. Such means may comprise, for example, a continuous flexible cable or cord 60 (Figs. 3 and 4) which runs over pulleys 61 arranged at the corners of the frame 21 and supported on such frame. A 65 spring-pressed take-up roll 61' serves to maintain the cable under tension. It will be clear with the arrangement illustrated that if certain portions of the cable 60 are caused to move to the right, certain other portions will be caused 70 to travel to the left at an equal speed. I make use of this fact by securing the respective ends of the hairline 50 to two parts of the cable which are adapted to travel in the same direction and by attaching the ends of the hairline 51 to parts 75

of the cable which are adapted to move in the opposite direction. Thus, at the side of the frame 21 nearest to the observer in Fig. 1, the inner strand of the cable is attached to the hairline 50 and the outer strand to the hairline 51. At the far side of the frame the order of attachment is reversed.

A possible mode of connecting the hairlines to the cable 60 is shown in Fig. 5 which represents a section taken on line 5-5 of Fig. 4. In this figure it appears that the hairline 50 is secured to the dependent end of an element 62 which forms part of a clamp fixedly engaging the cable 60. The other part of this clamp is formed integrally with an outwardly extending handle 63 which is adapted to be manipulated by the operator. A longitudinally extending slot 64 formed in the frame 21 (see Fig. 4) permits the clamp to be moved to the right or left while confining its motion to the proper plane. A slot 65 formed in the frame 20 (Fig. 1) also permits unobstructed lengthwise motion of the handle 63. Referring to Fig. 3 it is apparent that such motion necessarily produces simultaneous convergent or divergent movement of the hairlines 50 and 51. As previously explained, the effect of this simultaneous motion is to cause the hairline image to appear to move in a plane transverse to the observer's line of vision.

Simultaneous motion of the hairlines 50 and 51 in a common direction is effected by moving the frame 21 on which they are both mounted. As is shown clearly in Fig. 3, this frame is movably supported from the outer frame 20 so as to make this motion possible. The supporting means comprises guides 66 fixed to the frame 21 and slidingly engaging holes or bearing surfaces in the frame 20. The motion of the frame 21 may be accurately controlled by means of a thumb screw 68 (Figs. 3, 12 and 15) which is adapted to exert either propulsive or retractive force on the frame (see Fig. 15).

It has already been pointed out that motion of the hairlines 50 and 51 in a single direction serves to cause their common image to appear to move in a direction parallel to the line of vision, that is to say, in the third dimension of the object under observation. A further important aspect of the invention consists in a provision of means by which such apparent motion may be interpreted in terms of true measurements in such third dimension. In the embodiment of the invention which I have particularly illustrated, this is accomplished by the combination of a part movable with and in accordance with the motion of the frame 21 and a stationary part adapted to provide measurements in accordance with such motion. These elements are shown in detail in Figs. 11 and 12.

Prior to describing the measuring means fully, it is desirable to consider in some detail the conditions under which stereoscopically related views are initially obtained. In Fig. 10 I have illustrated an arrangement conventionally employed in obtaining stereoscopically related X-ray photographs for use in the examination of opaque bodies such as castings. In this figure the object of study is represented at 70 and is assumed to have embodied therein a defect, indicated at G, which it is desired to discover and locate precisely. To this end the object 70 is supported above a film supporting surface 72 adapted to receive a film which is sensitive to the action of X-rays. With the film in place, a first radiograph is taken by means of X-rays projected

from an X-ray tube, the target of which is illustrated at 73. Thereafter, the exposed film is removed and another similar film substituted in its place. A second picture is then obtained by the use of another X-ray source 74 displaced from the first by a distance A.

It is apparent that with the conditions illustrated, the first radiograph obtained will embody a picture of the defect G at a point G' determined by the projection of rays of X-light 75 proceeding from the target 73 through the defect G onto the film surface. Similarly, the second radiograph will include a picture of the defect at point G'' as determined by a projection of a ray of X-light 75' proceeding from the target 74 through the defect. The displacement V_g between these two pictures which would be noted if the respective radiographs were superimposed is obviously a function of the tube shift A; of B, the tube-film distance; of C, the object-film distance; and of X, the unknown height of the defect G. As a matter of fact, this relationship can be expressed mathematically by the equation

$$X = \frac{BV_g}{A + V_g} - C \quad 25$$

Since A, B and C are constants and are presumably known to the operator the quantity X can be readily computed once V_g is known. It is an important feature of my invention that it combines optical means for determining V_g with means dependent on such determination for computing mechanically the value of X. Exemplary instrumentalities by which this result may be accomplished are shown in Figs. 11 and 12. The elements of these figures will first be described structurally in detail and then with reference to their function and operation.

As previously suggested the measuring means comprises a stationary part or parts and a part which is movable in accordance with the motion of the hairlines 50 and 51. The stationary part includes in the first instance a scale 76 which is mounted in fixed relation on one end of the stationary frame 20. Adjacent to the upper end of this scale there is shown a second scale 77 which is at right angles thereto. At its left-hand end the second scale is formed integrally with a slotted member 78 which is adapted to interfit with and slide on the scale 76 (see Fig. 13). Adjacent the lower end of the scale 76 there is shown a third scale 80 which is also so mounted as to be slidable longitudinally of the scale 76. Cutting across the face of the scale 80 there is shown an index line which is illustrated as comprising a thread 83 but which may alternatively comprise the edge of a thicker member such as a rod or bar. The upper end of the thread is adjustably secured to the scale 77 by means of a rider 84 adapted to move along such scale. The position of this thread end (i. e. its spacing from the center line of the scale 76) may be ascertained by a reading obtained through a slot 85 appearing in the rider, which slot serves to make visible a narrow portion of the scale 77. The markings on the various scales are in linear units and should, for convenience, be in the same units on all scales.

At its lower end, the index member or thread 83 is wound on a spring driven drum 86 by means of which it is maintained under tension and biased against a stud or projection 87 (see Fig. 15) projecting upwardly from a member 87. This, in turn, is connected to the frame 21 so that when the frame is moved to the right or

left under the action of the thumb screw 68, the thread 83 is caused to travel across the face of the scale 80.

The mode of cooperation of the measuring device and the stereoscopic apparatus may best be understood by referring to the manner in which the former is used. Assuming the existence of two stereoscopically related views (photographs) of an object desired to be studied, it is necessary to "calibrate" the measuring device by setting up on its various scales, the known conditions under which the views were obtained. Thus, if a radiographic process such as that described in connection with Fig. 10 is involved, the position of the rider 84 is adjusted along the scale until the value read through the slot 85 is equal to the tube shift A (Fig. 10). The scale 71 is then moved as a whole along the scale 76 until its height as read on such scale corresponds to the known tube-to-film distance B. Finally the scale 80 is raised or lowered until its zero point 90 is at a point on the scale 76 corresponding to the object-to-film distance C.

In order to assure proper correlation of the viewing apparatus and the measuring device, the latter is "set on zero" by turning the thumb screw until the index thread 83 cuts the zero point 90 of the scale 80. If the apparatus is now properly adjusted, this should indicate a coincidence of the hairline image with the bottom plane of the object image. This condition may or may not be actually fulfilled, and if it is not, it will be necessary to make a further adjustment.

Such further adjustment is accomplished by moving the mirror 24 to the left or right by sliding the blocks 26. Since the mirror is more or less rigidly joined to the frame 20, this latter member also moves, carrying with it the inner frame 21 and the hairlines 50 and 51. Consequently, the apparent position of the hairline image as received in the mirror is not affected.

The pictures 31 and 32, on the other hand, remain stationary since they are supported independently of the frames. The resultant relative motion of the mirror and pictures causes apparent motion of the object image in a direction parallel to the observer's line of vision. By proper adjustment of the mirror this image can be caused to reach a position where its bottom plane appears to coincide with the hairline image—this being the condition desired to be attained.

In order to facilitate the adjustment just referred to, it is convenient to have some readily identifiable index element associated with the bottom plane of the object under consideration. In the case of radiographic studies this may suitably comprise a lead shot or other dense body embedded in the lower surface of the object as indicated at D in Fig. 10. If this is the expedient actually employed, the condition of the measuring device of Figs. 11 and 12 after the adjustments just described will provide a geometric arrangement exactly similar to that formed by the ray 75 and the dotted ray 96 in Fig. 10. That is to say, the intersection of the thread 83 with the center line of the scale 80 (Fig. 12) will simulate the intersection of the ray 96 (Fig. 10) with the ray 75 at the bottom plane of the object 70. (The zero line of the scale 80 represents the bottom plane of the object.)

If the thumb screw 68 is now turned in such a way as to move the frame 21 to the left the lower end of the thread 83 will move with it and the point of intersection of the thread and the center line of scale 80 will move up on the scale.

If the apparatus is to operate in the desired manner, the hairline image of the stereoscopic apparatus should come into coincidence with the image of the defect G at the instant that the reading of scale 80 is such as to indicate the location of such defect (that is, the distance X of Fig. 10). That this desired condition will necessarily be fulfilled may best be understood by a further consideration of Fig. 8.

As has already been explained in connection with that figure, coincidence of the hairline image with the image of any specified object occurs when the displacement between the directly viewed hairline 51 and the "virtual" hairline 50' is precisely the same as the displacement between the directly viewed picture and the virtual picture of that object. (This is the condition which is actually fulfilled in Fig. 8). In the event of a zero reading of the scale 80, the displacement of the real and virtual hairlines corresponds (after proper adjustment of the apparatus) to the displacement of the real and virtual pictures D' and D''' of any representative element (say, a lead shot) in the bottom plane of the object under consideration. If this element corresponds to the element D of Fig. 10, it can be shown that the hairline displacement in question is necessarily equal to the distance V_d (since V_d actually represents the stereoscopic displacement of the two radiographic pictures of D).

The effect of shifting both hairlines without changing their relative spacing is to increase the apparent displacement between the real and virtual hairlines (this is illustrated by the contrast between Figs. 7 and 8). Furthermore, due to the doubling effect of the mirror, a given amount of hairline shift will produce precisely twice that amount of change in displacement between the real and virtual hairline images. This also may be seen by comparison between Figs. 7 and 8.

Referring to a particular case, if both hairlines are moved to the left by motion of the frame 21, the hairline 50 may be brought to position 50a where it is in alignment with the object picture G''. By symmetry, the virtual hairline 50' will also move to 50'a into alignment with the virtual object picture G'''. Consequently, the hairline image will become coincident with the object image G. (G is considered to be the defect represented in Fig. 10.)

The resultant change in the distance between the hairline 51 and the virtual hairline 50' is equal to the difference between the distance V_g and the distance V_d (Fig. 10). However, the actual amount of hairline shift (as produced by moving frame 21) is equal to one-half the difference between V_g and V_d. (This is another consequence of the motion doubling effect of the mirror 24). In order that this factor shall not prevent the true operation of the measuring device it is necessary that all the elements of this device be half scale. That is to say, the various scales 76, 71, and 80 should be given lengths precisely half those which they are supposed to represent.

With this condition fulfilled, since any motion of the frame 21 imparts a similar motion of the bottom end of the indexing thread 83, it is clear that after the shift just referred to the arrangement of the thread and the center line of the scale 76 must duplicate the geometrical pattern made by the rays 75 and 75' of Fig. 10. That is to say, if the horizontal setting of the rider 84 corresponds to A, the vertical position of the scale 77

to B, and the distance between the zero points of the scales 76 and 80 to C, the displacement of the lower end of the thread 83 from the zero point of the scale 76 must, after the adjustment just described, correspond to the quantity V_x of Fig. 10. Finally by the principle of similar triangles, the reading of the scale 80 (i. e. the distance from its zero point to the point of intersection of its center line with the thread 83) must correspond to the 10 distance X which it is desired to determine.

Summarizing then, the use of the apparatus in analyzing stereoscopically related views consists in the following steps: The various scales of the measuring device are set to simulate the spatial 15 conditions under which the views were obtained; next the thumb screw 68 is turned to provide a zero reading of the scale 80 as determined by the position of the thread 83, and the mirror 24 is adjusted so that such zero reading corresponds 20 to coincidence of the hairline image seen by the observer with the image of some point at the bottom plane of the object under consideration. Thereafter, the thumb screw 68 is further adjusted to bring the hairline image into coincidence 25 with the image of the defect desired to be located. This will result in a reading of the scale 80, determinative of the location of the defect.

It should be noted at this point that a correct reading of the scale 80 will be obtained even 30 though the hairline image does not coincide with the defect image as long as it does fall in the same horizontal plane as that image. Complete coincidence of the two images may be obtained in order to improve the accuracy of the operator's 35 judgment by producing a convergent or divergent motion of the hairlines (by adjustment of the handle 63) to cause apparent motion of their image in a direction transverse to the line of vision. It should be clearly understood that this operation 40 has nothing to do with the functioning of the measuring device but simply makes it easier for the operator to determine when the hairline image is on the same apparent level (i. e. in the same horizontal plane) as the defect image.

I have found that the scale 76 must be of an 45 inconveniently great length if it is to be adopted for registering the values of the quantity B which are frequently encountered in actual practice. I have, therefore, provided means for obtaining the 50 effect of a relatively great extension of such scale without actually requiring any physical extension thereof. Such means comprises the use of a rider 84 having a character and shape as described in the following.

In order to accomplish the desired effect, the 55 upper surface of the rider should be in the form of a smooth arc having a radius of curvature linearly equal to the scale extension desired to be obtained. When the conditions are such that the extended portion of the scale is to be used, the upper end of the thread 83 is rendered freely 60 movable with respect to the rider by the use of a bearing element 100 adapted to roll in a groove provided for that purpose in the rider surface. 65 This feature is illustrated clearly in Fig. 14 in which 84 is the rider and 100 is the rolling element.

From a consideration of Fig. 16, it will be seen 70 that with the element 100 free to move over the surface of the rider, the thread 83 will, as long as it is under tension, seek a position in which it is normal to the arc which forms such surface. Furthermore the direction line of the thread will, if extended, pass through the center of generation 75 of the arc. The resultant effect is thus

precisely the same as though the upper end of the thread were fixedly attached at 0, and the motion of the thread 83 with respect to the scale 80 will be the same as though this condition were fulfilled.

As long as the actual (unextended) length of the scale 76 is sufficient to permit the distance B to be duplicated thereon, the rolling element 100 is immovably secured to the rider 84 by means of a spring clip 102 adapted to receive and retain the 10 same. With this arrangement the readings of the left-hand side of the scale 76 are utilized. However, when a greater scale length is required, the rolling element 100 is released and the scale 15 readings to the right of the center line of scale 15 76 are used. By means of these alternative modes of use the flexibility of the apparatus is greatly increased.

Although I have described my invention in connection with radiographic analysis, it is also applicable in connection with the preparation of contour maps from stereoscopically related aerial photographs. In this latter use the quantities 20 which must be known comprise the height of the plane from which the photographs are taken, the 25 distance traversed between photographs and the height of some one point appearing in the photographs.

In using these data the first quantity (plane 30 height) is set up on the scale 76; the second (camera shift) is set up on the scale 77, and the third is used to calibrate the apparatus in accordance with the "zero setting" operation previously described. The intermediate scale 80 need not be employed since all height values will be measured 35 from a common reference (ordinarily sea level). In other words, no quantity corresponding to the object-film distance C (Fig. 10) will be involved.

While I have in the foregoing described a particular structural embodiment, it will be understood 40 that many modifications may be made by those skilled in the art without departing from the invention. I, therefore, aim in the appended claims to cover all such variations of structure and use as come within the true spirit and scope 45 of the foregoing disclosure.

What I claim as new and desire to secure by Letters Patent of the United States, is:

1. A stereoscopic apparatus comprising a reflecting member providing a substantially plane reflecting surface, means for supporting a pair 50 of stereoscopically related views on opposite sides of said member and in planes transverse thereto, a pair of similar indexing elements, each arranged to be associated with one of said views during the use of the apparatus and each adapted for motion parallel to the plane of its associated view, and means operable to produce simultaneous divergent or convergent motion of the indexing elements with respect to the reflecting member or alternatively to move the elements simultaneously in a single direction with respect to such member.

2. A stereoscopic apparatus comprising means 65 providing a substantially plane reflecting surface arranged to be viewed grazingly by an observer, means for supporting a pair of stereoscopically related views of an object to be investigated on opposite sides of said surface and in planes transverse thereto, the mode of support being such 70 that by the aid of the reflecting surface the views may be observed simultaneously so as to afford a single stereoscopic image thereof, a pair of similar indexing elements, each arranged to be associated with one of said views during 75

- use of the apparatus and each adapted for motion parallel to the plane of support of its associated view, the elements also being so positioned that they may be viewed simultaneously by the aid of the reflecting surface to provide a single stereoscopic image thereof, means for simultaneously moving the indexing elements convergently toward or divergently away from the reflecting surface to cause apparent motion of their common image in a plane transverse to the observer's line of vision and means for simultaneously moving the members in a single direction to cause apparent motion of their image in a plane parallel to the line of vision.
15. 3. A stereoscopic apparatus comprising a table or frame for supporting in a single plane a pair of stereoscopically related views of an object to be studied, a mirror supported between such views and having its reflecting surface in a plane substantially normal to their plane of support, a pair of hairlines arranged on opposite sides of the mirror and in parallelism with its reflecting surface, each of said hairlines being arranged for motion over the surface of one of said stereoscopically related views, means for simultaneously moving the hairlines convergently toward or divergently away from the mirror, and means for moving the hairlines simultaneously in a common direction without disturbing the spatial relationship between them.
4. A stereoscopic apparatus comprising means providing a substantially plane reflecting surface, means for supporting a pair of two dimensional views of an object to be investigated on opposite sides of said surface and in planes transverse thereto, the mode of support being such that by the aid of the reflecting surface the views may be observed simultaneously so as to afford an image of the object having apparent extension in a third dimension, a pair of similar indexing elements each arranged to be associated with one of said views during the use of the apparatus and each adapted for motion parallel to the plane of support of its associated view, the elements also being so positioned that they may be viewed simultaneously by the aid of the reflecting surface to provide a single stereoscopic image thereof, means for simultaneously moving the members in a single direction to cause apparent motion of their image in said third dimension and means including a part adjustable in accordance with the motion of said elements for interpreting the apparent position of their image in terms of true measurements in said third dimension.
5. A stereoscopic apparatus comprising means providing a substantially plane reflecting surface, means for supporting a pair of stereoscopically related views of an object to be investigated on opposite sides of said surface and in planes transverse thereto, the mode of support being such that by the aid of the reflecting surface the views may be observed simultaneously so as to afford a single image of the object having apparent extension in a third dimension, a pair of hairlines arranged on opposite sides of said reflecting surface so that by the aid of said surface they may be viewed simultaneously to provide a single stereoscopic image thereof, each hairline being associated with one of said views and being adapted for motion parallel to the plane of support of its associated view, a movable frame supporting both of the hairlines, means associated with the frame for simultaneously moving the hairlines convergently towards or

divergently away from the reflecting surface to cause apparent motion of their common image in a plane transverse to the observer's line of vision, means for moving the frame and hairlines to cause apparent motion of the hairline image in said third dimension, and means dependent on the motion of the frame for interpreting the apparent position of the hairline image in terms of true measurements in said third dimension.

6. In combination, a stereoscopic apparatus of the type which employs a pair of two-dimensional views of an object under investigation to provide an image of the object which has apparent extension in a third dimension, means including a pair of similar indexing elements associated with the apparatus for providing a stereoscopic indexing image which has a desired optical relation to the object image, means for moving the elements to produce apparent motion of the indexing image in said third dimension, and means for mechanically and automatically interpreting the apparent position of said indexing image in terms of true measurements in said third dimension, said last named means including a scale-bearing member whereon such measurements may be read directly, an indicating member cooperating with said scale-bearing member, calibrating means for adjusting the relative positions of said members in accordance with the conditions, both of angle and distance, under which the said two-dimensional views of the object were taken, and a connection between one of said members and the means employed for moving the said indexing elements, said connection being effective to change the positional relationship of the said scale-bearing and indicating members in accordance with the motion of said indexing elements.

7. In combination, a stereoscopic apparatus of the type which employs a pair of two-dimensional views of an object under investigation to provide an image of the object which has apparent extension in a third dimension, means including a pair of similar indexing elements associated with the apparatus for providing a stereoscopic indexing image which has a desired optical relation to the object image, means for moving the elements to produce apparent motion of the indexing image in said third dimension, and means for mechanically and automatically interpreting the apparent position of said indexing image in terms of true measurements in said third dimension, said last named means including a scale-bearing member whereon such measurements may be read directly, an indicating member cooperating with said scale-bearing member, a plurality of auxiliary scales associated with said scale-bearing member for preliminarily adjusting the relative positions of said members in accordance with the conditions both of angle and distance under which the said two dimensional views of the object were taken, and a connection between one of said members and the means employed for moving the said indexing elements, said connection being effective to change the positional relationship of the said scale-bearing and indicating members in accordance with the motion of said indexing elements.

8. In combination, a stereoscopic apparatus of the type which employs a pair of two-dimensional views of an object under investigation to provide an image of the object which has apparent extension in a third dimension, means including a pair of similar indexing elements

associated with the apparatus for providing a stereoscopic indexing image which has a desired optical relation to the object image, means for moving the elements to produce apparent motion of the indexing image in said third-dimension, a scale-bearing member associated with the apparatus, a movable member providing a reference line angularly intersecting the scale of said first named member, calibrating means for preliminarily adjusting the angular relationship and point of intersection of the line and scale in accordance with the conditions of angle and distance under which the said two-dimensional views of the object were taken, and a mechanical connection between the said movable member and the means employed for moving the indexing elements, said connection being effective 5 to change the positional relationship of said scale and reference line in accordance with the motion of the indexing elements thereby to interpret the apparent position of said indexing image in terms of true measurements in said third dimension. 10

CHARLES D. MORIARTY.
